UNITED STATES PATENT OFFICE.

JOHN F. NISSLY, OF LANCASTER, PENNSYLVANIA.

BOTTLE OR JAR CAPPING MACHINE.

No. 838,134.

Specification of Letters Patent.

Patented Dec. 11, 1906.

Application filed December 20, 1904. Serial No. 237,677.

To all whom it may concern:

Be it known that I, JOHN F. NISSLY, a citizen of the United States, residing at Lancaster, in the county of Lancaster and State of Pennsylvania, have invented certain new and useful Improvements in Bottle or Jar Capping Machines; and I do hereby declare the following to be a full, clear, and exact description of the invention, such as will enable others skilled in the art to which it appertains to make and use the same.

The object of my invention is to provide a machine for the purpose of rapidly and certainly placing caps or similar closures in the tops of bottles or jars, it being particularly designed for putting in place thin disks, such as are commonly used for closing milk-bottles after they have been filled.

The machine is constructed to cap a number of bottles at one operation and to fit the disks or caps perfectly into the necks of the bottles, as will be hereinafter more fully described and claimed.

Referring to the accompanying drawings, which are made a part hereof and on which similar reference characters indicate similar parts, Figure 1 is a front elevation, the parts being in position for capping just before the beginning of the capping operation. Fig. 2 is a side elevation on the handle side with some of the parts at the bottom broken away to show details. Fig. 2^a is a detail of the guide-pieces. Fig. 3 is a top plan view with some of the parts at one side removed to show details. Fig. 4 is a detail plan view of the lower cross-plate, showing cap-feeding slide-plates and tube attachments. Fig. 5 is a longitudinal vertical section in detail on the line 5-5 of Fig. 4, showing especially various stages of operation of feeding and forcing in the caps. Fig. 6 is a detail of bracket and journal devices and of the strike or bearing-faces. Fig. 7 is a detail of the cap-feeding slide-guides with the parts slightly separated. Figs. 8, 9, and 10 are details of the centering devices.

The machine comprises, essentially, a supporting-frame which carries a table on which are placed and manipulated the crates carrying the milk-jars and in which is journaled an operating-shaft bearing the devices for reciprocating a pair of frames within the support and to and from the milk-jars. These reciprocating frames carry two substantially parallel and opposite cross-plates. Extending between these two cross-plates and passing

through the top one are a series of disk or cap holding tubes. To the upper cross-plate are secured a series of spring-wound cap-forcing plungers, while to the lower plate are secured a series of centering devices which take over the tops of the milk-jars.

Between the cap-holding tubes and plungers and the centering devices is a perforated cap-feeding slide which is reciprocated laterally by the same movement which reciprocates the frames and their connected parts vertically. The purpose of these features is to permit the caps to drop from their tubes into the perforations of the cap-feeding slide, to bring the centering devices over the mouths of the milk-jars so that there may be formed an accurate channel for the passage of the caps or disks into the mouths of the bottles, to laterally reciprocate the cap-feeding slide so as to bring the caps in line with the centering devices and the mouths of the bottles, and then to vertically reciprocate the plungers after the centering devices are rested upon the tops of the milk-bottles, to force the caps through the passage formed by the telescoped centering devices into the mouths of the jars, and, finally, return the parts to the retracted position.

There are various details of mechanism which provide for adjustability of the various parts and for accurate operation. It will be observed that by one movement of a hand-lever I gently center the feeding-channel over the bottles, reciprocate the cap-feeding slide, and bring down the plungers to force the caps into the tops of the bottles, and that my mechanism is adapted to be readily and easily operated with any size of jars, and that the machine is, in effect, an automatic bottle-capping device.

The supporting-frame comprises, as herein illustrated, two side bars 15, connected at the top by a bar 16. A similar connection may be formed at the bottom; but I have not deemed it necessary to illustrate the lower part of the machine.

Both the upper part of the machine and the lower part of the machine are braced in a familiar manner, as illustrated, by the brace-rods 17. Across the lower part of the machine extends a brace-rod 18, which also serves an additional function, as hereinafter described. The brace-rods 17 may be made adjustable in a familiar manner, as indicated at 19. The side bar 15 has an offset or extension 20, which is intended to carry the

guideways 21, on which slide the crates 22, bearing the milk-jars 23. This feature of the machine has various adjusting devices, which will be hereinafter described.

24 represents two guide-posts, one on each side, which are supported in sleeves 25, attached to the side bars 15. 26 is a bar or rod joining the two guide-posts at the top. These guide-posts, as will be observed, extend up beyond the top of the side bars 15 and form the ways upon which play the reciprocating frames and their parts, as hereinbefore mentioned. The guide-posts also serve to support the journal for the operating-shaft and its adjunctive features. At 27 is illustrated a bracket secured at 28 by a bolt 30 to the top of the side bar 15 and having a sleeve 29 embracing the guide-post 24 and secured thereto by a set-screw 31, there being one on each side of the machine. These parts are illustrated especially in Figs. 2 and 3, where they are shown in relation to the machine, and in Fig. 6, where they are shown in detail. At right angles to the sleeve 29 and in the illustrated form integral therewith is a sleeve forming a journal-bearing 32, in which is journaled an operating-shaft 33, which carries at one side a handle 34. This shaft bears at each end of the machine a pinion 35. It is the function of the handle, the shaft, and the pinion to operate the reciprocating frame and its connected parts, now to be described.

The reciprocating frame in the form illustrated is a skeleton or yoke 36 bearing two sleeves, an upper and a lower, 37 and 38, which play upon the guide-posts 24. A rack-bar 39, meshing with the pinion 35, is secured at each end to one side of each yoke of the reciprocating frame by bolts and nuts 40 41. To further indicate the manner of connection of the frame and the rack-bars, I have numbered the nut of the upper bolt 40 as 42, these nuts being taper-headed bolts secured thus from the inside. 43 indicates the lower bars of the reciprocating frames. Secured to these lower bars 43 of the reciprocating frames at each side at the point 44 is a plate 45, extending across the machine. This cross-plate 45 carries the plungers and receives the heads of the cap or disk holding tubes. 46 represents a bracket attached to the top of the plate 45. This bracket has at its center two sleeves 47 48, which embrace and play upon a center guide-post 49. This guide-post 49 has at its top a cap 50, limiting the upper movement of the bracket and its sleeve 47, and between the two sleeves a collar 50^a, secured at a predetermined point to the center guide-post 49 and having extending pins 50^b, by which, when desired, the guide-post may be lifted together, with the connected plates, plungers, and disk-tubes. At 50^c I have illustrated a notch into which one of the pins 50^b may be placed when it is

desired for any purpose to hold the parts in an elevated position. The center guide-post 49 extends downward through the cross-plate 45 and through a lower cross-plate resting at the bottom in a tubular bearing 51, supported on each side by braces 52, Fig. 4.

The lower cross-plate, which holds the centering devices, is shown at 53.

54 is a screw-threaded rod turning in a threaded bearing 55 and engaging at its inner reduced end a recess in the bottom of the center guide-post 49.

56 represents a series of cap-holding tubes which are set in base-rings 57, attached to the plate 53, and are received by corresponding perforations in the plate 45. These cap-tubes have each a slot at 58, by which the progress of the disks 59 may be observed. Weights 60 are preferably used in connection with the caps or disks to feed them downward, and in the form illustrated the handle of this weight projects through the slot of each cap-tube.

61 represents a series of plungers secured in the form illustrated by nuts and washers 62 to the cross-plate 45 and depending therefrom. Each of the plungers carries an encircling spring 63, operating at one end against the nuts and washers 62 and at the other end against a ring 64, secured to the top of the hollow head 65. This construction permits the head 65 to play on the shaft of the plunger in operation.

The cross-plate 53 has a series of perforations 66, which correspond with the mouths 100 of the centering devices through which the caps are fed, as hereinbefore described. The plate 53 is cut out on each side at 67 to receive a pair of parallel cap-feeding slides 68. The function of these slides is to receive the 105 caps from the cap-holding tubes and place them in the perforations of the plate 53. Each of these plates is narrowed at one end, the right-hand end, for example, in Fig. 4, and they are secured between guide-strips 69 110 by the bolts 70, securing the strips to the plate 53.

71 represents a pair of antifriction-rollers carried in a bracket 72, secured at one end to an end piece on the plate 53. Each of the 115 cap-slides 68 bears a series of perforations 73, which are slightly larger than the caps, so that the caps may readily fall into them as the perforation passes beneath its relative cap-holding tube.

At 74 I have represented a bell-crank lever which is to reciprocate the cap-slides 68 at each vertical reciprocation of the frames 36 and their connected parts, including the parts attached to the plates 45 and 53. The bell-crank lever is pivoted at 75 to an arm 76, depending from the cross-plate 53. The bell-crank lever carries at its upper end a roller 76, which plays between bearing-faces 77 and 78, arranged as to be described for the pur- 130

pose of giving the proper or desired reciprocation to the cap-slides.

79 is a plate secured by a screw 80, passing through a slot 81, so that the plate 79 may be secured to the side of the journal 32 and adjusted transversely thereon.

82 represents a lug secured by a bolt 83 to the side of the plate 79, which is slotted to receive the bolt, so that the lug 82 may be adjusted vertically to regulate the position of the lower face 78.

84 is an extension at the bottom of the plate 79 below the face 77. This extension provides a guide for the roller 76 in case it should play out of the line of the faces 77 78. I thus provide an adjustable strike, bearing-face, or cam-track for the operation of the bell-crank lever 74, so that it may be adjusted with precise relation to the requirements of a particular machine.

85 illustrates a pair of weights suspended by chains 86 from pulleys 87, turning in journals carried by brackets 88, which are secured to the cross-brace 16, the end of the chains 25 passing over the pulleys being attached to the cross-plate 45.

89 represents a pair of guide-arms which extend from the top plate 45 to the lower plate 53 and may be so adjusted as to form an 30 alining abutment for the lower plate 53 and its attached centering devices. The guide-pieces 89 have a right-angle upper part 90, secured freely by a bolt 91 to the plate 45 and having a set-screw 92 at the outer end. 94 is 35 a knee formed upon the upper arm 90, bearing against a rib 95 on the plate 45. By means of the set-screw 92 on the knee 94 these guide-pieces may be accurately adjusted to the proper plane to form guides for the 40 operation of the lower cross-plate 53 and its connected parts.

As has before been stated, each perforation of the plate 53 has its corresponding centering device. These centering devices comprise a cylindrical body 96, having a wing-plate 97 near the top, which in the form I have illustrated is generally triangular in form and has at each point an attaching device 98. The part or body 96 has at the top 45 a thicker neck with a beveled mouth and a lower seat 100. Concentric with the body 96 and playing within it is a cylindrical body or part 101, bearing on one side a slot 102, through which passes a threaded bolt 103. 50 The inner body 101 is beveled at the top and has a range of movement which enables this beveled top 104 upon the full stroke to seat upon 100.

105 represents a flaring or bell mouth, substantially funnel-shaped, enveloping both the cylindrical bodies and secured upon them by the threaded bolt 103. In the body 96 there is also formed a slot 102^a. By this construction the inner body 101 may have a 55 movement upon the bolt 103, while the bolt

103 may move upward within the slot 102^a. At Figs. 9 and 10 these parts are illustrated in their two extreme positions, and it will be observed that in Fig. 10 the mouth 105 has been driven up until it rests against the wing 97, a 70 recess having been provided to receive it, while the inner body has passed up within the body 96 until its bottom is substantially flush with the outer body and its beveled upper end stops against the seat 100. By this 75 construction a cap passes readily into the beveled mouth of the body 96 and from that gradually into the channel formed by the bodies 96 101, which are arranged in such relation to the size of the caps that they must 80 be forced through by operation of the plunger.

I have already briefly described the slideways 21 in which the crates 22 are placed. These slideways are, in effect, angle-irons, and 85 to accentuate this I have illustrated the sides of the ways by the reference-numeral 106. It is desirable to adjust these guideways to adapt them to receive various-sized crates. To this end I have provided beneath these 90 guideways and attached to the extensions 20 of the side bars 15 slotted plates 107, whose longer arms are secured to the extension 20 by means of bolts 108 and whose shorter arms are secured to the guide-rails 21 by means of 95 bolts 109. It will be readily seen that by this simple means the rails may be brought nearer together or placed farther apart to fit varying widths of crates. I have also found it advisable to provide adjustable stops to 100 regulate the position of the crates upon the guideway so that a crate may be slid in and stopped at the desired point and yet readily removed. To this end I have provided beneath the guideways 21 a post 110, secured 105 to a set-screw 111 to the brace-rod 18, so that it may be adjusted along the brace-rod to any desired point. In the top of the bar 110 rests a post 113, having a bifurcated upper part in which is journaled a roller 114. 115 represents a slot in a front plate of the bar 110, from which passes a bolt 116, the bolt being threaded into the end of the post 113. By this means the post 113 and the roller 114 may be adjusted vertically to any desired 115 point. At 117 I have shown an arm which is attached to the bottom of the post 113 and carries a spring 118, which is secured to the side of the post 110, so that the pin or post 113 may have a spring movement, thus permitting the roller-stop 114 to yield when a 120 crate is pushed forcibly against and over it.

The general operation of the machine is as follows: The parts being in the position illustrated in the principal figures of the drawings and the cap-holding tubes filled with caps and the weights resting upon the tops of the disks, the lever 34 is forced downward by the operator to turn the shaft 33 and the attached pinions 35. The rotation of these 130

pinions operating upon the rack-bars 39 will reciprocate the frames 36, and with these frames will travel down all the connected operative parts, the bracket 46, the guide-post 49, and the cross-plates 45 and 53, with their connected features. The downward movement of all these parts will of course bring the bells 105 of the centering devices over the tops of the several milk-jars 23 in the crate 22, which are positioned on the guideways 21 against the stop-roller 114. The flared or bell mouth of each centering device coming over the mouth of the corresponding bottle will draw the bottle to a position directly beneath and in line with the inner cylindrical part or body 101, so that the mouth of the bottle will be in position to receive its cap and will be thus brought to position and finally adjusted with a gentle movement which will not in any way injure the bottle. The inner cylindrical body 101 in this movement will slide upward or telescope within the outer cylindrical body 96 until its tapered top 104 rests against the seat 100, passing from the position shown in Fig. 9 to that shown in Fig. 10. The illustration of these two figures assumes that the bottles are all of equal height. If, however, they should be of different height, that difference will be accepted and relatively adjusted by the proper operation of the telescope bodies of the centering devices. Furthermore, by this arrangement of the centering devices the guides for the caps are enabled always to be extended entirely to the neck of the bottle, and no space is left in which the cap may tilt or move sidewise out of position, the action being such that it always fits evenly and squarely in place. When these centering devices are thus finally adjusted and rest upon the tops of the bottles, the operative parts connected to the frames and the plates 45 and 53 will be supported by the bottles so that while the lower cross-plate 53 is held in this position the upper cross-plate 45, with its attached plungers, will continue to move downward, carrying with it the plungers 61. During the first part of the downward movement of the frames and their connected parts the bell-crank lever 74 has been operated upon by the strike or bearing face 77, so that its upper arm is forced inward toward the machine, turning it upon its pivot 75 and throwing outward its lower arm, so that the cap-feeding slides are drawn to the right toward the operator. This movement will bring the perforations 73, which have been immediately beneath the cap-holding tubes 56, to position directly over the entrance or channel of the centering devices. The caps lying in these perforations thus brought in line with the channel of the centering devices will drop directly into the tapered or beveled upper mouth of the cylindrical body 96 and will there be evenly adjusted for the succeeding

operation. In this position the upper arm of the bell-crank lever 74 is freed from the cam-tracks 77 and 78, so that it will not be operated by the subsequent operation of the connected features. The plungers 61 now force down the caps through the channel of the centering device and are thus guided into position in the necks of the bottles or jars, the channel being of such diameter that the caps will fit snugly therein, thus being prevented from tilting out of an even horizontal position. The coil-springs 63, encircling the shaft of the plungers, have sufficient force of tension to resist compression until the caps are forced into place in the necks of the highest bottles (if there should be any difference in height) and will in the subsequent downward operation compress so as to permit the caps to be forced into the succeeding bottles, including even the lowest. The breakage of bottles by being brought into contact with the rigid parts is thus guarded against, and an even seating of the thin disks is provided, so that they will rest firmly in place on all sides, thus meeting the difficulty inherent in preceding machinery of this type. These relative movements are indicated in Fig. 5. On the left hand in that figure the cap-feeding slide 68 has not yet moved forward to carry with it the lower cap. In the next section to the right it has moved forward and brought the cap over the channel of the centering devices, while the centering devices themselves are shown as resting on the top of the bottle or jar. In the third section—the one farthest to the right—plungers are shown as having forced the cap downward through the channel of the centering devices, and the parts are beginning to retract, assuming finally the position shown in the section farthest to the left.

The operation being thus completed, the operator releases or raises the lever 34, and the weights 85 then operate, through their connections with the cross-plate 45, to raise the parts, the cap-forcing plungers being first lifted until the bearing-collars 47 and 48 strike the collar 50^a and cap 50 on the guide-shaft or post 49, when the cross-plate 53 and the parts carried thereby will also be lifted to the position shown in Figs. 1 and 2 of the drawings. As the cap-feeding plungers reach the point above the cross-plate 53, freed from the perforations therein, and over the cap-feeding slides the lever 75 comes into engagement with the bearing-face 78 on the attachment 82, fixed to the bracket-plate 79, and during the remainder of the upward movement of the parts operates to throw the cap-feeding slides back to bring the perforations 73 under the cap-holding tubes 56 to again receive the lower caps of the columns of caps in the several tubes. By reason of the arrangement of the bracket-plate 79 and its adjustable parts the operation of the lever 74 may be regulated and timed in exact accordance with the opera-

tion of the other parts of the machine. The crate of bottles being thus capped is now ready to be removed. The stop 114 is forced down out of the way, and the crate is drawn off out of the machine and another crate is pushed into position at the same time and stopped in the proper place for the capping operation by the stop 114, which springs up into position as soon as the first crate passes over it. The operation is then repeated in cycles continuously, as above described. A crate of any number of bottles may be capped at one time. In the drawings I have illustrated a crate containing two rows of six bottles each; but it will be understood that the number may be more or less and that the machine may be provided with the number of parts corresponding to the desired number of bottles.

Having thus fully described my said invention, what I claim as new, and desire to secure by Letters Patent, is—

1. The combination of the supporting-frame having a table for supporting the crate of bottles to be capped, standards extending a distance above said table and properly braced, guide-posts extending vertically adjacent to said standards and braced at their tops, reciprocating frames mounted on said guide-posts to reciprocate thereon and carrying a cross-plate having cap-seating plungers mounted thereon, brackets mounted on the standards and guide-posts containing bearings and a transverse shaft mounted in said bearings, pinions on said shaft, an operating-lever also on said shaft, rack-bars mounted on said reciprocating frames engaging said pinions, vertical bearings mounted on said transverse plate, a vertical shaft mounted to slide in said bearings, a second transverse plate mounted on a lower end of said shaft, centering devices mounted on the under side of said second plate, cap-containing tubes on the top of said plate, and an automatic cap-feeding mechanism operated by the movement of said reciprocating frames, substantially as set forth.

2. A machine for capping bottles comprising a supporting-frame, a reciprocating frame mounted thereon, means for moving said frame up and down, cap-seating plungers mounted on said reciprocating frame, centering devices mounted on a plate secured on the lower end of a vertical shaft mounted to slide in vertical bearings, whereby they are adapted to remain stationary during a part of the movement of said plungers, the cap-holding casings, and mechanism for feeding the caps to the centering devices arranged to be operated by the movement of said reciprocating frames, substantially as set forth.

3. A machine for capping bottles comprising a supporting-frame, a table thereon for supporting the bottles in position to be capped, guide-posts mounted on said frame,

reciprocating frames mounted to slide on said guide-posts, a plunger-carrying plate secured to said frames, cap-seating plungers mounted on said plate, vertical bearings carried by said plate, a shaft mounted to slide in said bearings and extending to below said plate, a second plate mounted on the lower end of said shaft normally below said plungers, centering devices mounted on said second plate, and cap-feeding mechanism, substantially as set forth. 70 75

4. A machine for capping bottles comprising a supporting-frame, guide-posts thereon, reciprocating frames mounted on said guide-posts, a cross-plate carried by said reciprocating frames, plungers mounted on said cross-plate, a vertical shaft mounted in bearings carried on said plate, a second plate mounted on the lower end of said shaft, centering devices mounted on said second plate, 80 disk-containing tubes also mounted on said second plate, disk-feeding slides, and a pivoted lever engaging said slides and operated by the movement of the frame for moving said slides. 85 90

5. A machine for capping bottles comprising a supporting-frame, a reciprocating frame carrying plungers, a vertical shaft mounted to slide in bearings carried by said reciprocating frame, a plate extending across the machine and supported on the lower end of said shaft, centering devices and disk-guides mounted on the lower side of said plate around apertures therein, disk-carrying tubes mounted on the top of said plate, disk-feeding slides mounted in longitudinal ways in the top of said plate, a lever pivoted to the reciprocating frame and arranged with one end engaging a part connected to said slides and the other end engaging a strike fixed on a stationary part, whereby said slides are operated automatically by the movement of the reciprocating frame, substantially as set forth. 95 100 105

6. A machine for capping bottles comprising a supporting-frame, a reciprocating frame mounted thereon, plungers carried by said reciprocating frame, a vertical shaft mounted to slide in bearings also carried by said reciprocating frame, a plate mounted on the lower end of said vertical shaft, centering and disk guiding devices mounted on the under side of said plate around apertures therein, disk-holding tubes mounted on the top of said plate to one side of said apertures, disk-feeding slides provided with apertures mounted in ways in the top of said plate and adapted to slide back and forth under said tubes, a sliding plate mounted between ways on one end of said plate and connected with said slides, a bell-crank lever pivoted to the reciprocating frame and having one end engaging with said sliding plate and its other arranged to engage a strike on a stationary part during a part of the movement of the reciprocating 110 115 120 125 130

frame and operate said slides to feed the disks from the tube to the guiding and centering devices, substantially as set forth.

7. A machine for capping bottles comprising a supporting-frame, a reciprocating frame carrying the capping mechanism, mechanism for feeding the caps, a lever for operating said mechanism pivoted to the reciprocating frame and arranged to strike bearing-faces mounted in a fixed position alongside the reciprocating frame, the parts carrying said bearing-faces being adjustably mounted, whereby the time of the operating may be properly regulated, substantially as set forth.

8. A machine for capping bottles comprising a supporting-frame, a reciprocating frame carrying plungers, a vertical shaft mounted to slide in bearings carried by said reciprocating frame, a plate mounted on the lower end of said shaft, centering devices mounted on the under side of said plate, disk-holding tubes mounted on its top side, slides having perforations mounted in ways in the top of said plate and adapted to slide beneath the disks in said tubes and receive the lowermost one into one of said perforations, mechanism for operating said slides to carry said disks to said centering devices while they are being seated upon the bottles, and to return them to receive another disk of each pile while said centering devices are being raised from said bottles after the capping operation, substantially as set forth.

9. A machine for capping bottles comprising a supporting-frame, a reciprocating frame mounted thereon carrying plungers, a vertical shaft mounted in bearings on said frame, a plate having a central perforation fitting over the lower end of said shaft, a locking screw-rod mounted on the under side of said plate and engaging at its inner end with the lower end of said shaft for securing said plate thereto, centering devices on the under side of said plate, disk-holding and disk-feeding devices on the top of said plate, and means for operating said feeding devices by the movement of said reciprocating frame, substantially as set forth.

10. A machine for capping bottles comprising a supporting-frame, a reciprocating frame carrying the plungers, a vertical shaft mounted and adapted to slide in bearings on said frames, a plate mounted at its center on the lower end of said shaft carrying the centering devices and the cap holding and feeding devices and guides adjustably secured to said reciprocating frame and extending down on each side of said shaft to rest against one edge of said plate and hold it in proper position in relation to the other parts, substantially as set forth.

11. A machine for capping bottles comprising a supporting-frame, a reciprocating frame mounted thereon rack-bars mounted

on said reciprocating frame, a transverse shaft with pinions meshing with said rack-bars, means for operating said shaft, plungers mounted on said reciprocating frame, a central vertical shaft mounted in bearings on said reciprocating frame, a plate on the lower end of said shaft, centering devices on the under side of said plate around apertures therein, disk-holding and disk-feeding devices on the top of said plate and a supporting-table for the bottles beneath said centering devices, substantially as set forth.

12. A machine for capping bottles comprising a supporting-frame, a reciprocating frame carrying the capping mechanism, a table for supporting the bottles beneath said capping mechanism, a spring-mounted reciprocating stop mounted to slide horizontally on a portion of the frame and extending into the path of the crate containing the bottles as it is moved upon said table, and means for securing said stop in the position desired whereby the position at which said crate shall stop may be fixed, substantially as set forth.

13. A machine for capping bottles comprising a supporting-frame, a reciprocating frame mounted thereon carrying the capping mechanism, said capping mechanism embodying a centering device comprising a fixed cylindrical part mounted on the supporting-plate, a bell-shaped part mounted to slide thereon and an internal guide for the cap secured within said cylindrical part and adapted to slide with said bell-shaped part, substantially as set forth.

14. A machine for capping bottles comprising a supporting-frame, a reciprocating frame mounted thereon carrying the capping mechanism, centering devices mounted on the lower plate of said capping mechanism each comprising a fixed part, an outer part having a bell-shaped lower end mounted to slide on said fixed part and adapted to receive and center the mouth of the bottle, and an internal guide adapted to slide within said fixed part and to slide with and also independently of said outer bell-shaped part, whereby it will rest upon the top of the bottles regardless of their several heights, substantially as set forth.

15. A machine for capping bottles comprising a supporting-frame, a reciprocating frame carrying the capping mechanism, a lower plate mounted on a sliding support and carrying centering devices on its under side mounted around apertures in said plate, each of said centering devices consisting of a cylindrical part mounted within one of said apertures and being of an internal diameter at its upper end that will permit the passage of the caps therethrough only by force and formed with an offset a short distance beneath its upper end, an internal cylindrical guide mounted beneath said offset of an in-

ternal diameter corresponding with the upper end of said first-named part, a bell-shaped outer part mounted on said first-named part and connected therewith to slide thereon, 5 said internal guide being connected to each to slide independent of both, substantially as set forth.

16. In a machine for capping bottles, the combination with the other mechanism, of 10 a centering device comprising a cylindrical part secured to the supporting part, a centering-bell mounted to slide thereon, and an internal guide for the cap mounted to slide independent of both the other parts, substantially 15 as set forth.

17. In a machine for capping bottles, the combination with the other mechanism, of a centering device comprising a cylindrical part secured to the supporting part formed 20 with a tapered edge around its top and being of an internal diameter at its upper end to permit the passage of the guide therethrough only by force, an internal sliding guide-cylinder in said part and an outer centering-bell 25 connected therewith and mounted to slide on said first-named part, substantially as set forth.

18. A machine for capping bottles, comprising a supporting-frame, a reciprocating 30 frame carrying the capping mechanism, a bearing-face or cam-track mounted on the supporting-frame, mechanism for feeding the caps, a lever centrally pivoted to the reciprocating frame and arranged so that its 35 upper end will strike said bearing-face or cam-track and its lower end operate said cap-feeding mechanism when the machine is operated.

19. In a bottle-capping machine having a 40 supporting-frame and a reciprocating cross-head mounted thereon, said cross-head having an upper and an under plate, said upper plate carrying a two-jawed end lug or

bracket, said under plate having straps or cap-feeding slides mounted in the upper surface thereof, the combination with a plate secured to the top of said straps or slides and having ears, a pair of rollers pivotally supported by said ears, said last-mentioned plate having an aperture through its body 45 between said ears and rollers, of a lever-arm centrally pivoted to said lug or bracket, and its lower end in engagement between said rollers, the upper branch of said lever carrying a roller, means provided for engagement 50 with said latter roller to rock said lever and move said straps or slides, substantially as 55 described and for the purposes hereinbefore set forth.

20. In a bottle-capping machine having a 60 supporting-frame with end standards having rear end posts, the vertical guide-rods, and the bearing blocks or brackets, having shaft-bearings, said blocks or brackets rigidly secured to said rods and to the upper end of 65 said posts, and a reciprocating cross-head, with its end pieces sleeved on said guide-rods, said pieces carrying vertically-disposed rack-bars, the combination with said rack-bars of a rock-shaft having its end journaled 70 through said bearings, with pinions mounted on and rigidly secured to said shaft adjacent to the bearings, said pinions having their teeth to intermesh with those of said rack-bars, and a hand-lever with its hub end rigidly secured to the projecting end of the 75 shaft, whereby said shaft is rocked, said cross-head reciprocated, and the machine made to perform its functions.

In testimony whereof I affix my signature 80 in presence of two witnesses.

JOHN F. NISSLY.
